UNITED STATES PATENT OFFICE.

GEORGE W. LANGFORD, ALFORD C. BARROWS, AND CHARLES W. GOOD, OF ANN ARBOR, MICHIGAN, ASSIGNORS TO ECONOMY BALER COMPANY, OF ANN ARBOR, MICHIGAN, A CORPORATION OF MICHIGAN.

HIGH-DENSITY ATTACHMENT FOR COMPRESSES FOR COTTON BALES.

Application filed September 14, 1925. Serial No. 56,327.

The invention relates to high density attachments for compresses for cotton bales and has for one of its objects the provision of a mechanically driven high density attachment, including a side platen and mechanical driving means for quickly moving said side platen to operative position. Another object is to provide a simple construction of mechanical driving means, including a revoluble member and toggle levers connected to the side platen and actuated by the revoluble member. A further object of the invention is to provide a pivotal floor section for normally covering the gap between the fixed floor section and the compress when the side platen is in the lowered or inoperative position, this pivotal floor section and the side platen being arranged relative to each other so that the side platen engages the pivotal floor section and moves the same upwardly and away from the compress, thereby avoiding the liability of throwing a person upon the pivotal floor section into the compress. With these as well as other objects in view the invention resides in the novel features of construction and combinations and arrangements of parts as more fully hereinafter set forth.

In the drawings:—

Figure 1 is a side elevation of a compress for cotton bales having applied thereto a high density attachment embodying my invention;

Figure 2 is a sectional end elevation thereof;

Figure 3 is a similar view of a modified construction of high density attachment.

The compress for cotton bales has the vertical frame 1, which extends below the floor level into the pit 2. 3 is the upper platen which is stationary and fixedly secured to the frame 1 and 4 the lower platen which is vertically reciprocable from a position slightly below the floor level to a position near the upper platen. This lower platen is fixedly secured upon the saddle 5, which is guided by the frame 1 and is vertically reciprocated by suitable means including the toggle levers 6 connected at their lower ends to the opposite ends of the saddle and at their upper ends to the frame, these toggle levers being actuated by means of the links 7, which are connected to the gears 8

journaled on the frame. The gears for actuating the toggle levers at one end of the compress rotate in the opposite direction and at the same rate of speed as the gears for actuating the toggle levers at the other end of the compress. These gears are driven from a suitable prime mover (not shown) by means of the reduction gearing 9.

The high density attachment comprises the side platens 10 at the opposite sides of the compress which are adapted to be moved from inoperative to operative positions by mechanical driving means. The side platens and mechanical driving means for these side platens are alike and therefore the side platen and its mechanical driving means at one side of the compress only will be described in detail. As shown, the side platen 10 is pivotally mounted upon the frame 1 of the compress at a point substantially below the floor level, there being the fixed pivot 11 which connects the side platen to the frame. 75 This side platen is adapted to be swung upwardly and inwardly relative to the compress from an inoperative position where it lies substantially below the floor level to an operative vertical position at the side of the compress to form a side wall of the baling chamber. To swing this side platen upwardly and inwardly to operative position at a sufficient rate of speed to compress the cotton bale above the lower platen 4 prior to the time that compression of the bale takes place between the upper and lower platens of the compress and at the same time to form a simple construction of mechanical driving means for the side platen, we preferably provide the pair of toggle levers 12 and the bull gear 13 for actuating these toggle levers. The toggle levers comprise the lever 14 which is pivotally connected at 15 to the side platen near its free end and the lever 16 which is pivotally connected at one end by means of the pivot 17 to the free end of the lever 14, and which is connected at its opposite end to the fixed pivot 18. 19 is a link pivotally connected at 20 to the bull gear 13 and pivotally connected to the toggle levers by the pivots 17, the arrangement being such that upon rotation of the bull gear in the direction indicated by the arrow in Figure 2, the link 19 exerts a force upon the toggle levers 12 which straightens the

same, thereby swinging the side platen 10 upwardly and inwardly relative to the compress to its operative or vertical position.

The downward swinging of the side platen 5 is limited by means of a suitable stop 21 engageable with the lower side of the side platen.

The bull gear 13 for actuating one of the side platens meshes with the bull gear for 10 actuating the other of the side platens to thereby rotate the latter bull gear in the proper direction to straighten the toggle levers to which it is connected. For driving this bull gear there is the driving pinion 22, 15 which meshes with one of the bull gears and is rotated by a suitable prime mover (not shown).

With the arrangement as thus far set forth it will be seen that the side platens are 20 equally and simultaneously moved from their inoperative to their operative positions and furthermore that the time interval required between these movements is relatively short so that they will be in operative position 25 prior to the time of compression of the cotton bale between the upper and lower platens of the compress. It is also to be noted that at the time when the greatest stress is being applied tending to swing the 30 side platens downwardly, the toggle levers are straight or substantially so and oppose an effective resistance to the downward swinging of the side platens.

For covering the gap between the compress 35 and the stationary floor 23 when the side platens are in their lowermost or inoperative positions so that the cotton bale which has been compressed in the compress may be readily removed and replaced by another 40 cotton bale I have provided at each side of the compress the pivotal floor section 24, which is pivoted at 25 near the stationary floor and has a free end extending adjacent to the compress and over the side platen and its actuating mechanism. For swinging the 45 pivotal floor sections we have provided means upon the side platens for engaging these pivotal floor sections. Furthermore we have provided means upon these side platens 50 for bridging the gap between the main portions of the side platens and the pivotal floor sections when the latter are swung upwardly. As shown the pivotal floor sections have 55 their free ends resting upon these side platens and the side platens are further provided with the transverse curved horns 26 at their free ends, which are engageable by the free ends of the pivotal floor sections while the latter are in their upwardly swung positions. Thus it will be seen that the side 60 platens swing the pivotal floor sections upwardly and away from the compress to avoid throwing a person into the compress and further that the gaps between the free ends 65 of the pivotal floor sections and the main

portions of the side platens are closed by means of the transverse curved horns upon the side platens.

In the modified construction shown in Figure 3 the compress and the high density attachment therefor has the same general arrangement of parts with the exception that the link 27 which pivotally connects the bull gear 28 to the toggle levers 29 is pivoted at 30 to the free end of the rock lever 31, 75 which forms with the lever 32 the toggle levers. This rock lever has the fixed pivot 33 intermediate its ends. With this arrangement the link 27 is under tension instead of under compression, while the side platen is 80 being swung upwardly and inwardly relative to the compress to operative or vertical position.

What we claim as our invention is:

1. The combination with a compress for 85 cotton bales, of a high density attachment, including a side platen and means for actuating the same, including toggle levers connected to said side platen, a revolute member and a link between said revolute member and toggle levers for actuating the latter from the former.

2. The combination with a compress for cotton bales, of a high density attachment, including a pivotal side platen and means 95 for swinging the same to operative and inoperative positions, including toggle levers comprising a lever having a fixed pivot and a lever pivotally connected to said first mentioned lever and side platen, a revolute 100 member and a link pivotally connected to said revolute member and toggle levers.

3. The combination with a compress for cotton bales, of a high density attachment, including corresponding pivotal side platens 105 at opposite sides of said compress and corresponding means for swinging said side platens to operative and inoperative positions, including toggle levers correspondingly connected to said side platens and revolute gears connected to said toggle levers, said gears meshing with each other below said side platens.

4. The combination with a compress for 115 cotton bales, of a high density attachment, including an upwardly movable side platen and a pivotal floor section engageable by said side platen and movable upwardly thereby upon upward movement thereof.

5. The combination with a compress for 120 cotton bales, of a high density attachment, including a side platen pivoted at its lower end, means for swinging said side platen to operative and inoperative positions and a pivotal floor section engageable by said side platen and swung upwardly and away from said compress by said side platen during its movement to operative position.

6. The combination with a compress for 125 cotton bales having a vertically reciprocable

lower platen and a stationary floor substantially level with said lower platen when in its lowermost position, of a high density attachment for said compress, including a side 5 platen pivoted at its lower end, and means for swinging said side platen from a position at the side of said compress and substantially below the stationary floor level to a vertical position at the side of said compress, a pivotal floor section extending from said floor to a point adjacent to said compress and over said side platen when substantially below the floor level, and means upon said side platen engageable with said 10 pivotal floor section for swinging the same upwardly and outwardly away from said compress during the movement of said side platen to its vertical position.

7. The combination with a compress for 20 cotton bales, of a high density attachment including a side platen and means for actuating the same including toggle levers connected to said side platen and movable from operative to inoperative positions, a revolute member, and a link pivotally connected to said revolute member and toggle levers, the plane extending through the axes of the 25 link pivots extending adjacent to the axis of said revolute member when the toggle levers are in operative position to facilitate moving the toggle levers to operative position and also facilitate holding the toggle levers in this position.

8. The combination with a compress for 30 cotton bales, of a high density attachment, including a side platen pivoted at its lower

end, means for swinging said side platen to operative and inoperative positions, a pivotal floor section resting upon said side platen and substantially concealing the 40 same, said floor section adapted to be swung upwardly and away from said compress by said side platen during its movement to operative position, and a projection upon said side platen engageable with the floor 45 section when the platen is in operative position to hold the floor section in its upward position.

9. The combination with a compress for 50 cotton bales, of a high density attachment including a side platen and means for actuating the same including toggle levers connected to said side platen and movable from operative to inoperative positions, a revolute member, and means for actuating said 55 side platen from said revolute member including a link having pivotal connections at its opposite ends with one of the pivotal connections securing said link to said revolute member, the plane extending through the 60 axes of the pivotal connections extending adjacent to the axis of said revolute member when the toggle levers are in operative position to facilitate moving the toggle levers to operative position and also facilitate holding the toggle levers in this position. 65

In testimony whereof we affix our signatures.
